UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL STOVE.

Application filed July 19, 1919. Serial No. 311,953.

To all whom it may concern:

Be it known that I, RUDOLPH HOFFMAN, a citizen of the United States, residing at Kankakee, in the county of Kankakee and 5 State of Illinois, have invented certain new and useful Improvements in Oil Stoves, of which the following is a specification.

The invention relates to oil stoves of the type embodying a constant-level oil supply 10 reservoir and one or more burners adapted to be raised and lowered with reference to said constant level whereby to control the flow of oil from the reservoir to the burners. Such burners are usually supported beneath the stove top upon a horizontal stationary supply pipe, and to permit of the vertical movement of the burners with reference to said pipe an extensible pipe connection is employed between the burner and 15 supply pipe comprising two telescoping pipe sections.

Owing to the tendency of the oil to creep along a metallic surface by capillary attraction, I provide a liquid metallic seal of 20 mercury or the like for the joint between said pipe sections, which absolutely prevents the leakage of oil. One of the objects of this invention is to provide means of advantageous construction to form a closure 25 for retaining such mercury against escape when the stove is tipped up upon end or inverted as in shipping.

Another object of the invention is to provide improved means for effecting the raising and lowering movements of the burner with reference to the constant-oil level.

In the accompanying drawings, I have illustrated a preferred form of my invention. Fig. 1 is a side elevation of the lower 30 portion of an oil burner supported upon a stationary horizontal supply pipe. Fig. 2 is a vertical sectional view taken on line 2—2 of Fig. 1. Fig. 3 is a horizontal section taken on line 3—3 of Fig. 1. Fig. 4 is a vertical section taken on line 4—4 of Fig. 1. Fig. 5 is a horizontal section taken on line 5—5 of Fig. 4. Fig. 6 is a horizontal section taken on line 6—6 of Fig. 1. Fig. 7 is a fragmentary side elevation showing details 35 of construction.

In the drawings 1 designates the bowl or trough of an oil burner mounted upon a stationary horizontal pipe 2 which receives a supply of oil from a constant-level oil

reservoir (not shown) of well-known construction. 3 indicates generally an extensible pipe connection between the trough 1 and pipe 2, by means of which a supply of oil is conducted to the burner and maintained at a constant level in a well-known manner.

The extensible connection 3 between the burner bowl or trough 1 of the burner and the supply or delivery pipe 2 comprises two sections 3^a and 3^b carried respectively by the pipe 2 and trough 1. The inner section 3^a is made of a diameter slightly less than the diameter of the outer section 3^b and at its lower end is screw-threaded into a fitting 4 connected in a well-known manner to the delivery pipe 2 so as to communicate therewith. The pipe section 3^b is rigid with the lower edge of the burner bowl 1, being secured thereto as by brazing, and is adapted to freely receive the section 3^a.

The means for clamping the fitting 4 upon the delivery pipe 2 so that it shall be capable of firmly supporting the burner in its proper position, comprises a pair of links 5 and 6 operatively engaging with studs 7 and 8 upon opposite sides of the fitting and similarly connected to an intermediate block 9 below the pipe 2. Said block has a set screw 10 therein adapted to operatively engage with the pipe 2. By simply tightening said screw, the fitting 4 may be drawn downwardly onto the delivery pipe 2 and firmly clamped in position thereon.

For the purpose of providing an annular channel around the inner pipe section 3^a of the extensible pipe connection 3, for the reception of a quantity of mercury or the like in which the lower end of the pipe section 3^b may be immersed, I provide a tubular stem or member 11 carried by the fitting 4. This member is in the form of a pipe of a diameter substantially greater than the diameter of the pipe section 3^a and at its lower end is threaded into a socket 12 provided in the upper portion of the fitting 4. The pipe section 3^a and the tubular member 11 are thus concentrically arranged and are spaced apart to form a channel 13. Said channel is filled with a sealing liquid such as mercury 14 to a depth sufficient to cover the lower end of the outer pipe section 3^b in all operative positions of the latter relative thereto. It will be seen that oil standing in

the pipe section 3^a and overflowing into the space between it and the section 3^b is prevented from flowing around the lower end of the latter section by the mercury in the channel into which said section depends.

The means for raising and lowering the burner comprises a hand lever 15 pivotally mounted between its ends upon a bracket 16 and operatively engaging a member 17 guided for vertical movement upon the stem 11 and adapted to support a pair of pendant arms 18 rigid with the burner bowl 1. The lever 15 comprises a hand portion 15^a and a bifurcated portion 15^b, the arms of the latter being entered through slots 19 in the bracket 16. Herein said bracket is formed by an upward extension of the link 5, the upper end of the bracket being bent to form a lateral portion 16^a which is apertured to receive the stem 11. Upon the outer side of said bracket 16 is secured a plate 20 (Fig. 2) bent to form a journal bearing 20^a for a pivot 21 the opposite ends of which extend through the arms of the bifurcated portion of the lever to provide a pivotal mounting for the latter. The vertically movable member 17 is substantially U-shaped, comprising an upright portion 17^a having two laterally extending arms 17^b apertured to receive the stem 11. The arms of the bifurcated portion of the lever after passing through the slots 19 in the bracket 16 pass on opposite sides of the stem (Fig. 5) and operatively engage in slots 22 provided in the upright portion 17^a of the member 17. The pendant arms 18 of the burner are secured to the member 17 so as to be readily detachable therefrom whereby to permit of the removal of the burner from its supporting means. To this end the opposite edges of the member 17 are provided with notches 23 for receiving tongues 24 formed on the lower ends of the arms 18 spaced apart (Figs. 6 and 7) and beaded to receive the legs of a U-shaped member or staple 25 upon the forward side of the upright portion of the member 17. To permit of the insertion of the staple 25 into the beaded ends of the arms 18 in the notches 23, the upper arm of the U-shaped member 17 is notched at its side edges as at 26. At their upper ends the pendant arms 18 are brought together and are made of a width adapted to fit neatly within the burner bowl 1 to which they are rigidly secured in any suitable way.

It will be seen that by operating the lever 15 the burner may be easily raised or lowered with reference to the supply pipe 2. The upward movement of the burner is limited by the upper arm 17^b of the U-shaped member 17 engaging with the laterally extending portion 16^a of the bracket 16, and the extent of downward movement is limited by an annular member or collar 27 fixed

upon the outer pipe section 3^b of the extensible pipe connection and adapted to engage with the upper end of the stem 11.

It will be seen that the annular channel 13 formed between the stem 11 and the inner pipe section 3^a is normally open in the operative position of the parts, so that if the stove is tipped upon end or inverted, the mercury will escape from the channel unless prevented. In the present instance to prevent such escape of the mercury, the fitting 4 has cast integral therewith a storage receptacle or chamber in the form of a cylinder 28, and a passage 29 is provided in the casting between the lower end of the channel 13 and the lower end of the cylinder. This passage is adapted to be controlled by a valve member 30 screw-threaded into the casting (Fig. 3) and having a knurled head 31 by means of which it may be operated. The parts are so arranged that when the valve is open, the mercury will flow by gravity through said passageway into the cylinder, the lower end of the latter being disposed a substantial distance below the lower end of the mercury channel 13. Upon closing the valve, the mercury is effectively retained in the cylinder 28 so that the stove may be placed in any position desired without danger of the mercury escaping.

After the stove has been set up into its operative position, it is only necessary to open the valve 30 and force the mercury through the passage 29 into the lower end of the channel again. This may be accomplished by means of a plunger 32 mounted within the cylinder 28 and operable by means of a stem 33 operatively engaging the plunger at its upper end and having a screw-threaded engagement with a nut 34 screwed into the upper end of the cylinder. Upon the upper or outer end of the stem 33 is a knurled head 35 by means of which the plunger may be operated. With the valve 30 open, when the plunger is raised, the mercury flows into the lower end of the cylinder for storage therein while the stove is being shipped, and when the plunger is lowered, it forces the mercury from the cylinder into the lower end of the channel, after which the valve member may be moved into closed position.

If the burner is lowered too rapidly or very suddenly, the displacement of the oil in the extensible pipe connection by the lower end of the outer pipe section 3^b, causes the oil to spurt upwardly in the burner bowl 1 producing a splash. To overcome this objection, means may be provided for retarding the movement of the hand lever. Herein I have provided an arcuate member 36 mounted upon the bracket 16 and adapted to be frictionally engaged by the lever 15 in its up and down movements. Said arcuate member may

comprise a pair of spaced arms 37 (Fig. 5) adapted to engage with the opposite sides of the hand portion 15^a of the lever and thus providing a guideway therefor. Upon the forward one of said arms 37 suitable legends may be inscribed to indicate to the user the proper positions for the burner in use. Thus the words "Light", "Medium" and "Out" are inscribed upon the arms 10 (Fig. 1) to indicate that when the lever is positioned opposite these words, the burner is respectively positioned with its upper edge just above the constant oil level, is partially raised above the oil level, or is wholly raised above the oil level. The frictional engagement of the arms 37 with the lever 15 also insures that the burner may be maintained in any desired position against the action of gravity.

20 It will be seen that I have provided in an oil stove employing mercury or the like for preventing the leakage of oil past the joint between the pipe sections of the extensible pipe connection, means of advantageous construction for retaining the liquid when the stove is inverted, as in shipment. The raising and lowering means for the burners are also advantageous, being simple in construction and easily operable to effect the 25 raising and lowering movement of the burners as may be desired. Claims directed to the mercury seal per se are contained in my copending application Serial No. 308,542, filed July 3, 1919; and the claims drawn 30 to the raising and lowering means have been divided out and placed in my copending application, Serial No. 509,376 filed October 21, 1921, which is a continuation in part of this application.

40 While I have herein illustrated and described the invention with considerable particularity, I desire to have it understood that in the interpretation of the appended claims they are not to be limited except as 45 may be necessitated by the state of the prior art.

I claim as my invention:

1. In an oil stove, the combination of an oil supply pipe and a burner mounted for vertical movement with reference to said pipe, of an extensible pipe connection between said burner and said pipe comprising a pair of telescoping pipe sections, means providing an annular channel for the reception of a metallic liquid for sealing the joint between said pipe sections, and a chamber in valved communication with said channel adapted to receive such metallic liquid and retain it while the stove is inverted.

2. In an oil stove, the combination with an oil supply pipe and a burner, of means for raising and lowering the burner, and means for conducting a supply of oil to the burner comprising a sectional pipe, means

providing a metallic liquid seal for sealing the joint between said pipe sections, and means providing a separate chamber for receiving the metallic liquid when the stove is to be inverted.

3. In an oil stove, the combination with an oil supply pipe and a burner, of means for raising and lowering the burner, and means for conducting a supply of oil to the burner comprising a sectional pipe, means 75 providing a metallic liquid seal for sealing the joint between said pipe sections, an auxiliary chamber adapted to receive the metallic liquid, and valve means for closing said chamber.

4. In an oil burner, the combination with an oil supply pipe and a burner, of a fitting on the supply pipe, an extensible pipe connection between the burner and supply pipe comprising an inner pipe section rising 85 from the fitting and an outer pipe section depending from the burner, a tubular stem surrounding the inner pipe section and adapted to form therewith a channel for receiving the outer pipe section and a quantity 90 of mercury or the like, a chamber below the lower end of said channel, a passage-way connecting said channel with said chamber, and a valve for controlling said passage-way.

5. In an oil burner, the combination with an oil supply pipe and a burner, of a fitting on the supply pipe, an extensible pipe connection between the burner and supply pipe comprising an inner pipe section rising from 100 the fitting and an outer pipe section depending from the burner, a tubular stem surrounding the inner pipe section and adapted to form therewith a channel for receiving the outer pipe section and a quantity of 105 mercury or the like, a chamber below the lower end of said channel, a passage-way connecting said channel with said chamber, and a valve for controlling said passage-way, and means for forcing the mercury 110 from the chamber to the channel by way of said passage-way.

6. In an oil stove, the combination with a source of oil supply and a burner, of a fitting communicating with said source of supply, a pair of relatively stationary pipe sections rising from said fitting and spaced apart to form an annular channel therebetween for the reception of mercury or the like, a relatively movable pipe section rigid 115 with said burner and adapted to depend into said mercury, a cylinder having its lower end terminating a substantial distance below the lower end of said channel and in valve-controlled communication therewith, 120 and a plunger operable in said cylinder to force the mercury therefrom into said channel by way of said passage.

7. In an oil stove, the combination with a burner and a source of oil supply, of an 130

extensible pipe connection including a pair of telescoping pipe sections between said source of supply and said burner and having a metallic liquid seal between the relatively 5 movable pipe sections, and means forming a closure for said metallic liquid while the stove is inverted comprising a cylinder, valve-controlled means for admitting the liquid seal to and from said cylinder, and 10 means for forcing the metallic liquid to pass from said cylinder into its operative position.

8. An oil stove having an extensible pipe connection including a pair of telescoping 15 pipe sections, a chamber surrounding said pipe connection for receiving a quantity of mercury or the like to seal the joint between said pipe sections, and an auxiliary storage chamber in valve-controlled communication 20 with the first mentioned chamber.

9. In an oil stove, the combination with a source of oil supply and a burner, of an extensible pipe connection between said source of oil supply and the burner having a 25 sliding joint, means forming an annular chamber for the reception of a mercury seal for the joint of said extensible pipe connection, means providing a chamber for the reception of the mercury, and means for 30 causing the mercury to pass from one of said chambers to the other.

10. In an oil stove, the combination with an oil burner and a source of oil supply, of a sectional pipe connection, a cylinder having a plunger therein, a screw stem for operating said plunger, an annular channel for receiving a quantity of mercury or the like adapted to seal the joint between the sections of said pipe connection and valve-controlled 35 means for controlling the flow of mercury between said channel and said cylinder.

11. In an oil stove, the combination with a source of oil supply and a burner, of an extensible pipe connection between said source of oil supply and the burner having a sliding joint, means forming an annular chamber for the reception of a mercury seal for the joint of said extensible pipe connection, means providing a chamber for the 40 reception of the mercury, and valve-controlled means for controlling the flow of mercury between said chambers.

12. The combination of an oil supply 45 pipe, a burner, means providing an extensible pipe connection between said pipe and

said burner permitting of the up and down movements of the latter, means providing a seal to prevent the leakage of oil by capillary attraction from said extensible pipe connection including a chamber for supporting a quantity of mercury or the like, and an auxiliary chamber for receiving the mercury so as to retain it in the inoperative condition of the burner. 60

13. The combination of an oil supply pipe, a burner mounted for up and down movement and having an extensible pipe connection with said supply pipe, means including a chamber associated with said connection providing a metallic liquid seal therefor, and means independent of said chamber for providing a closure for the metallic liquid adapted to be sealed to prevent the escape of mercury therefrom. 70

14. In an oil stove, the combination with a source of oil supply and a burner, of an extensible pipe connection between said source of supply and said burner comprising two telescoping sections having a metallic liquid seal therebetween, means providing a chamber adapted to receive such metallic liquid, means forming a passageway connecting said chamber with said channel, and means for controlling the flow 80 of the metallic liquid between said channel and chamber. 75

15. An extensible conductor for oil or other fluid comprising two telescoping pipe sections, a chamber for retaining a quantity 90 of mercury or the like into which the free end of the outer pipe section is adapted to be immersed, and an auxiliary chamber for the mercury in communication with the first chamber. 95

16. In an oil stove, the combination of a stationary oil supply pipe, a burner, an extensible connection between said pipe and said burner permitting of the up and down movements of the latter, said connection 100 comprising a pair of telescoping pipe sections, means providing a chamber for the reception of a metallic liquid in which the free end of the outer pipe section is adapted to be immersed, an auxiliary storage chamber 105 communicating with the first chamber, and means operatively associated with said extensible connection for effecting the up and down movements of the burner.

In testimony whereof, I have hereunto set my hand.

RUDOLPH HOFFMAN.
